SUPERHETERODYNE RADIO RECEIVER

Richard F. Shea, Fairfield, Conn., assignor to
 General Electric Company, a corporation of
 New York

Application January 7, 1942, Serial No. 425,910

10 Claims. (Cl. 250—20)

1

My invention relates to superheterodyne radio receivers and more particularly to such receivers adapted for operation over two or more frequency bands.

My invention has for one of its objects to provide a superheterodyne radio receiver having simplified and improved means whereby it is adapted for operation over the broadcast band and over two or more, so-called "spread" bands. That is, the receiver is provided with a band selector switch which in one position connects the receiver for variable tuning, by means of uncontrolled tuning elements, over the broadcast band, and which, in another position, connects it for variable tuning by means of the same uncontrolled tuning elements over a short wave range including a plurality of desired bands, which may be termed "spread" bands. An object of my invention is to provide an economical arrangement whereby the variation in the position of the tuning control member in these spread bands to produce any given change in tuning of the receiver is as great as possible.

The receiver may be provided with a plurality of calibrated tuning scales one for the broadcast band and one for the short wave range including the "spread" bands, over which the receiver is tunable when the band selector switch is in its alternate or short wave position. The desired "spread" bands may fall near the opposite ends of the calibration for the short wave range. An object of my invention is to provide a system in which the spread bands may occupy a portion as great as possible of the linear length of this short wave scale while the range of frequencies between these "spread" bands, which may include a greater portion of the frequency spectrum than the spread bands include, is crowded into as small as possible portion of this scale.

One circuit arrangement which may be considered for band spread operation, such as I have described, comprises an inductance coil, having a tap, the tuning condenser being connected between the tap and one end of the coil through a padding condenser and being shunted by a trimming condenser, the whole coil being connected between the grid and cathode of a tube of the receiver, which may be either an amplifier or oscillator. With such a circuit, if the padding condenser be small, most of the change in frequency to which the receiver is tunable occurs upon variation of the tuning condenser only over one end portion of its movement. That is, the curve expressing the relation between increments of movement of the tuning condenser and variation of tuning effected thereby is very steep at one end and progressively reduces in pitch toward the other end. This crowds the corresponding calibrations of the dial scale at one end of the scale. Alternatively the trimming

2

condenser which shunts the tuning condenser may be made large. This results in a reduction of the inductance of the coil employed thereby reducing the gain obtainable if the circuit be used in an antenna stage, or unstable oscillation if the circuit be used in the local oscillator. This also crowds the calibration at the opposite end of the dial scale if the variable condenser be one shaped in the conventional fashion.

10 A further alternative is to omit the trimmer and connect the tuning condenser, if it be of high capacity, across a small portion of the coil, or if it be of low capacity, across the whole coil. This results in good gain and stable oscillation but it also has the effect of producing most of the frequency variation at the said opposite end of the movement of the tuning condenser and of crowding the calibrations of the dial scale at that end.

20 In accordance with my invention, when using a large tuning capacity, as, for example, one having a maximum capacity of 450 micromicrofarads, it may be connected across a fairly small portion of the coil through a moderately high 25 value of series padding capacitance comparable to the maximum capacity of the tuning condenser, the whole coil being shunted by a trimmer. Such an arrangement produces a tuning curve which has its steepest portion near the 30 middle and which reduces in pitch toward both ends thereby spreading out the frequency bands in which we are interested along the calibration scale and avoiding the crowding at either end previously described.

35 Where the tuning condenser is small as, for example, one having a maximum capacity of 120 micromicrofarads it may be connected directly across the whole coil thus obviating both the tap and the series padder and at the same time pro-

40 ducing the desired spreading of the calibrations at both ends of the dial scale. This arrangement, in addition to these advantages, is especially desirable in the oscillator circuit since the small tuning condenser in the oscillator is particularly advantageous in securing tracking with the larger tuning condenser in the signal input circuits over the broadcast band. Thus, in accordance with my invention this small tuning condenser, which is highly desirable in the broad-

45 cast band, may be switched into the short wave circuit and there serves to spread the calibrations of the dial scale near both ends of the short wave range over which the receiver is tunable. This local oscillator circuit then determines the

50 tuning curve of the receiver and the problem reduces to that of tracking with the tuning condenser in the signal input circuit. Since a larger tuning condenser is necessary in the input circuit for tuning in the broadcast band, the short wave input circuit may be one of the type just

described in which the large tuning condenser is used. This circuit includes both a shunt trimmer and a series padding condenser which may be used for adjustment of the tuning curve to agree with the oscillator tuning curve. By such adjustments entirely satisfactory tracking of these two circuits may be secured over both bands of frequencies, the calibrations for which are situated at opposite ends of the dial scale. In fact, the two tuning curves may be made to cross in the center of both of the desired spread bands.

In addition the circuit arrangement in the signal input circuit necessary to track with the oscillator circuit of such design permits, and, in fact, requires, the use of a large inductance coil, which may comprise a loop antenna, and which because of its large size has increased response to a received signal and thus contributes very desirably to the sensitivity of the receiver.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which Fig. 1 represents an embodiment of my invention; Fig. 2 represents the variable capacitors employed therein; Figs. 3, 4 and 5 represent certain characteristics pertaining to the form of the invention shown in Fig. 1; Fig. 6 represents a further embodiment of my invention; and Figs. 7 and 8 represent characteristics pertaining to the embodiment of the invention shown in Fig. 6.

Referring to Fig. 1 of the drawing, I have shown therein the circuits of the initial stages of a radio receiver which may incorporate my invention. This receiver may comprise a pair of receiving loop antennae represented on the drawing by coils bearing the reference numerals 1 and 2 respectively. These coils may selectively be connected between the grid 80 and cathode 81 of a radio frequency amplifier 3 by means of the various armatures of a selector switch 4. The received oscillations are amplified in the amplifier 3 and supplied from output electrode or anode 82 through a coupling capacitance 5 to the input circuit of an electron discharge device 6, which may be utilized as a converter, to convert the received oscillations to oscillations of low or intermediate frequency. These intermediate frequency oscillations may appear in a circuit 7 and may then be supplied through additional tuned circuits as desired to subsequent portions of the receiver, not shown. The electron discharge device 6 comprises a cathode 8, an anode 9 and five grids arranged in succession between the cathode and anode. The first two grids 10 and 11 act respectively as the control electrode and anode of a local oscillator, the inductances of which for operation in the different frequency bands, are represented at 12 and 13 respectively. The third grid 83 acts as the input electrode for the high frequency oscillations.

For operation in the broadcast band of frequencies the inductance 1 of the input circuit and the inductance 12 of the local oscillator circuit are utilized, the inductance 1 having its upper terminal connected through contact *a* and the upper armature 14 of the switch 4 to the input electrode 80 of the amplifier 3 and its lower terminal connected to a point of ground radio frequency potential, which may be the conductor 15

upon which a unidirectional potential of variable intensity for purposes of automatic volume control may be impressed. This conductor is grounded for radio frequency potentials by condenser 25. The coil 1 is connected in shunt, through armature 16 of the switch 4, with the variable tuning condenser 17 whereby the inductance 1 may be tuned over the broadcast band.

The inductance 12 of the local oscillator is likewise connected in shunt with the tuning condenser 18 by means of armature 19 of the switch 4 through the lower portion of the short wave coil 13, the inductance of which may be negligible at the frequencies involved in reception in the broadcast band of frequencies. Coil 12 is also shunted by trimmer condenser 12'. By broadcast band of frequencies I have reference to frequencies extending from the neighborhood of 500 kilocycles to the neighborhood of 1700 kilocycles. For operation in the broadcast band the circuit 12, 12', 18 may resonate at a frequency approximately 455 kilocycles higher, or lower, than the frequency of the received signal to which circuit 1, 17, is resonant thereby to produce currents having a frequency of 455 kilocycles in the intermediate frequency circuit 7.

If it be desired to effect reception by means of a vertical antenna such as the ordinary outdoor antenna for home use, a number of additional turns of wire may be incorporated in the mechanical structure of the loop 1 to couple inductively such an antenna to the inductance of the loop 1. Such additional turns may be represented by the inductance which I have indicated at 26 as connected between ground 21 and an antenna indicated at 22, through a suitable resistance 23 if desired.

For operation in the short wave band the switch 4 may be thrown to its lower position to engage the contacts marked *b* in which case inductances 1 and 12 are removed from their respective circuits and inductances 2 and 13 are inserted. Tuning condenser 17 is then connected by means of armature 16 of switch 4 through padding condenser 24 to a tap upon the coil 2 and thence to ground through condenser 25. The upper terminal of the coil 2 is connected to the input electrode of the discharge device 3 through the armature 14, and the whole coil is shunted by the trimmer condenser 26.

Tuning condenser 18 is then connected across the entire coil 13 through the armature 19 of the switch, and is shunted by a trimmer condenser 28. The vertical antenna 22 may be connected to a tap on the short wave antenna loop 2 if reception from such antenna be desired.

The variable condensers 17 and 18 which are connected together for unicontrol operation by a common operating shaft 24 may be provided with any desired form of calibration. Commonly these calibrations are in the form of dial scales such as those indicated at 29 and 30 of Fig. 5, these scales being arranged on a dial on the front of the cabinet housing the receiver and having an index cooperating therewith and movable along the scales in linear relation with the variation of the tuning condensers 17 and 18 which are, of course, arranged for unicontrol. The scale 29 corresponds to the broadcast band and is calibrated in frequency from the neighborhood of 500 kilocycles to approximately 1700 kilocycles. The scale 30 corresponds to the short wave band and is calibrated in frequency from below 9.5 megacycles to something over 12 mega-

cycles. The two bands of short wave frequencies to be received are those commonly called the 25 meter band and the 31 meter band, the 25 meter band extending in frequency from approximately 11.5 megacycles to 12 megacycles and the 31 meter band extending from approximately 9.5 to 9.8 megacycles as indicated by the heavy portion of the line 30 in Fig. 5.

The intermediate portion of the short wave range, namely, that portion extending from 9.8 megacycles to 11.5 megacycles, corresponds to a portion of the frequency spectrum utilized principally for code transmission and its not particularly desirable for the purposes for which receivers are utilized in which I contemplate my invention to find its greatest usefulness. I contemplate the receiver of my invention more particularly for home reception and, accordingly, since programs suitable for such reception are transmitted on frequencies in the 25 meter band and the 31 meter band, my invention is intended to facilitate tuning the receiver to frequencies in those bands.

In accordance with my invention, the frequencies to which the receiver is tuned by movement of the tuning control member in the 25 meter band and the 31 meter band are spread out as widely as possible on the two portions of the scale corresponding to these ranges of frequencies, of course, at the expense of the remaining portion of the scale corresponding to frequencies reception of which is only of secondary interest.

To accomplish this band spreading of the 25 and 31 meter bands, a condenser 18 smaller in capacity than the condenser 17 is employed. These condensers may be, for example, of the form shown in Fig. 2 in which the rotor of the condenser 17 is indicated at 31 and the rotor of the condenser 18 is indicated at 31', the rotor 31' being very substantially smaller than that indicated at 31. The condenser 18 may have a maximum capacity of, for example, 120 micromicrofarads, whereas the condenser 17 may have a maximum capacity of 450 micromicrofarads. These condensers may have capacity which varies with rotation thereof in the manner expressed by the curves C_A and C_O in Fig. 3, the capacity of the condensers being plotted as ordinates at the right end of the figure and the percentage of rotation thereof being plotted as abscissae.

In the broadcast band the condenser 18 of small capacity is connected directly across the coil 12, there being no padde condenser present in the circuit. The condenser 17 is likewise connected directly across the coil 1 without the use of any padde. These inductances 1 and 12 may be proportioned to tune over the broadcast frequency band and the two circuits to track with each other in accordance with the relationships indicated by the curves T_A and T_O of Fig. 3. These curves T_A and T_O of Fig. 3 represent the relation between the movement of the tuning condensers plotted as abscissa and the frequency to which the receiver tunes plotted as ordinates, the full line curve T_O being the curve pertaining to the local oscillator and the dotted line curve T_A being that pertaining to the circuit 17, 1. These curves substantially coincide throughout the broadcast band.

Since no padding condenser is present in either circuit and only the oscillator circuit employs a trimmer, adjustment for the alignment of the two circuits is secured by adjustment of trimmer 12' and by suitably bending the plates of one or

both of the condensers. Condenser 31 has peripheral notches cut therein to permit such bending.

When switch 4 is in its high frequency position, the condenser 18 is connected directly across trimmer condenser 28 and inductance 13, and the condenser 17 is connected through the padde condenser 24 to the tap on coil 2 as previously described, the whole of coil 2 being shunted by the trimmer condenser 26.

The tuning curve for the local oscillator is then indicated by the full line curve of Fig. 4 in which the rotation of the condenser is plotted in terms of percent of the rotation as abscissa and frequency in megacycles as ordinates. It will be seen that this curve is steepest in the intermediate portion of the band between, for example, 10 megacycles and 11.5 megacycles, whereas the slope reduces at points beyond this range. The dotted line curve of Fig. 4 represents the tuning relationships in the tuned input circuit 2, 11. It will be observed that this dotted line curve crosses the full line curve at the middle point of the two spread bands, namely, the 25 meter band and the 31 meter band, and hence accurate tracking of the two circuits results. The adjustment to obtain the crossing in the 25 meter band may be secured by variation of the trimmer condenser 26 and that in the 31 meter band, may be obtained by a variation of the padde condenser 24.

The value of the padde condenser 24 which may be employed is affected by the inductance of the conductors extending from this condenser 24 through switch 16 to condenser 17. This inductance is represented on the drawing at 24' in Fig. 1. The greater this lead inductance is the less is the value of capacitance required to produce the desired tracking.

With my invention the dial may be calibrated substantially as indicated in Fig. 5. It will be seen that the calibrations of the short wave scale are not only not crowded at either end of the scale, but instead, are spread out at both ends of the scale even more than in the middle of the scale. For example, on the scale of Fig. 5, which may be assumed to be five inches in length, the 25 meter band, which is but half a megacycle wide, may occupy an inch of the linear length of the scale, and the 31 meter band, which is only three-tenths of a megacycle wide, may occupy substantially three-fourths of an inch of the scale. On the other hand, in the middle of the short wave range between, for example, 10.5 and 11 megacycles, a half megacycle occupies substantially eleven-sixteenths of an inch and is thus considerably more crowded than either the 25 meter band or the 31 meter band.

The advantage in spreading of the calibrations secured by my invention, however, is not truly evaluated by such linear comparisons unless it be borne in mind that with conventional circuits one of the two spread bands is decidedly crowded with respect to the intermediate portion of the total short wave range over which the receiver is tunable. The calibration secured by my invention is in striking contrast to those secured by such circuits.

Of course, while I have mentioned condenser 18 as being small and as having a maximum capacity in the neighborhood of 120 micromicrofarads, a larger condenser may be employed in this position and if it have capacity considerably greater than 120 micromicrofarads it may be connected across a part of the coil through a padde. It is

necessary, however, that the shape of the condenser plates be such as that indicated by curves CA and CO of Fig. 3, thereby to produce the reduced slope of the tuning curves near the ends thereof. It will be observed that curve CO, corresponding to the oscillator condenser, is of reduced slope near both ends thereby producing the reduced slope near the ends of the tuning curves of Fig. 4. The condenser 18 may be of shape such that its capacitance curve is of the shape of the curve CA of Fig. 3 but in this case a series padder is required to reduce the slope of the tuning curve in the range corresponding to high capacity positions of the tuning condenser.

Fig. 6 represents my invention incorporated in a receiver having two short wave bands each of which includes two spread bands in which desired signals, or programs are broadcast. Elements of Fig. 6 corresponding to those of Fig. 1 bear similar reference numerals. Switch 4 comprises a plurality of armatures 35, 36, 37 and 38 employed to effect the desired connections of the input circuit for operation over the different bands, and a plurality of armatures 39, 40, 41, 42, and 43 to effect the desired connections of the local oscillator circuit for operation over the various bands.

During operation in the broadcast band tuning condenser 17 is connected through armature 36 directly across the antenna loop 1, the lower terminal of which is grounded through condenser 25. Similarly, the tuning condenser 18 is connected through armatures 42 and 40 directly across coil 12, there being no padder present in either circuit.

For operation in the first short wave band the switch 4 may be rotated counterclockwise to the first position. Condenser 17 is now connected to a tap on the short wave antenna coil 2 through a padding condenser 46. The entire coil 2 is connected through armatures 35 and 38 between the input electrode of device 3 and ground, and a portion thereof is shunted by a trimmer condenser 47. Condenser 18 is connected through armatures 42 and 40 across the whole of oscillator coil 13, which is shunted by the trimmer condenser 28 as in Fig. 1.

These connections produce the tuning characteristic indicated at 50 in Fig. 7 in which it will be observed that the 31 meter band and the 49 meter band corresponding to frequencies to be received fall on portions of the curve having less slope than the intermediate portion of the curve, and correspondingly these bands are spread out on the tuning dial which may be represented by the upper portion 51 of Fig. 8 where these bands are designated by suitable legends.

For reception in the next higher frequency band the switch is rotated counterclockwise again to its last position. In this position the condenser 17 is connected through armature 36 and padder 52 to a higher tap on the coil 2, and an additional trimming condenser 53 is connected across the entire coil through armature 37. The tap to which condenser 47 is connected is grounded. Thus only the upper portion of the coil is in use. The oscillator condenser 18 is now connected to a tap on the coil 13, the latter being shunted by a trimming condenser 28.

The tuning curve is now that represented by the curve 60 of Fig. 7 in which it will be observed that the 19-meter band extending from 14.8 megacycles to 15.6 megacycles falls upon a portion of the curve of reduced slope as does also the 25 meter band, which extends from 11.6 megacycles to 12 megacycles. It will likewise be observed

from Fig. 8 that the calibrations corresponding to these bands are spread out along the scale 81 to a greater extent than are the intermediate frequencies.

Adjustments for securing the operation represented by Figs. 7 and 8 with the equipment of Fig. 6 is similar to that described in connection with Fig. 1. The shape of the tuning curve is, of course, determined by the condenser 18 and the inductance in shunt therewith, this condenser 18 having a maximum capacity in the neighborhood of 120 to 240 micromicrofarads. The radio frequency circuit then by means of series padders and shunt trimming condensers, is adjusted to produce a characteristic similar to the tuning curve of the oscillator and one which preferably intersects the tuning curve of the oscillator in the intermediate portions of the spread bands to be received as was described in connection with Fig. 4. Here, again, the value of capacitance of condensers 46 and 52 required to produce the desired alignment is affected by the inductance of the leads leading to condenser 47, this inductance being represented on the drawing at 46' and 52' respectively.

It will be noted that the oscillator circuit of my invention for the short waves is of the same form as that used for the broadcast band. The change in the form of the tuning curve from that shown in Fig. 3, which is satisfactory for the broadcast band, to that shown in Fig. 4 for the short wave band results directly from the use of the smaller tuning inductance in the local oscillator, together with the increased shunt capacity in the trimmer.

The shape of curve determined by the oscillator requires the type of circuit described for the tuned input circuit including both the shunt trimmer and the series padder. The tuning condenser employed in the input circuit is large, as it must be because of the requirements of the broadcast band. Since the short wave band is narrow it must be tapped down on the antenna inductance. This is advantageous since the tuning inductance is desirably large. The tuning inductance may be that of the loop antenna, which has greater response to the intercepted signal if made large rather than small. Thus, my invention contributes directly to improved sensitivity of the receiver.

Switch 4 in Fig. 6 may also be rotated in a clockwise direction to connect the receiver for tuning by means of push buttons which may activate switches 65, 66, 67, 68 and 69 in the input circuit and 70, 71, 72, 73 and 74 in the local oscillator circuit. These switches may be arranged in any suitable well-known way to connect one of the condensers 65', 66', 67', 68', 69' in the signal input circuit and one of the inductances 70', 71', 72', 73', 74' in the oscillator circuit for adjustment of the circuits for tuning to a particular frequency. Such means have no relation to my present invention and will not be further described.

While I have shown particular embodiments of my invention, it will, of course, be understood that I do not wish to be limited thereto since various modifications may be made both in the circuit arrangement and in the instrumentalities employed, and that I contemplate by the appended claims to cover any such modifications as fall within the true spirit and scope of my invention.

What I claim as new and desire to secure by Letters Patent of the United States is:

1. In a superheterodyne receiver having an input tuned circuit, and a local oscillator circuit, said circuits including respective capacitors arranged for unicontrol, switching means to alter said circuits for operation in different frequency bands, said circuits being proportioned when said switching means is in one position to be tuned by said capacitors over a broad range of low frequencies and when said switching means is in another position to be tuned by said capacitors over a range of high frequencies, said range of high frequencies including two desired bands of frequencies, one at each end thereof, and an intermediate range of undesired frequencies, and means to reduce the variation in frequency produced per unit of movement of said uncontrolled capacitors in the extreme regions of said high frequency band corresponding to said desired bands of frequencies with respect to the variation produced in the intermediate portion of said high frequency band corresponding to said range of undesired frequencies.

2. In a superheterodyne receiver having an input tuned circuit, and a local oscillator circuit, said circuits including respective capacitors arranged for unicontrol, switching means to alter said circuits for operation in different frequency bands, said circuits being proportioned when said switching means is in one position to be tuned by said capacitors over a broad range of low frequencies and when said switching means is in another position to be tuned by said capacitors over a range of high frequencies, said range of high frequencies including two desired bands of frequencies, one at each end thereof, and an intermediate range of frequencies, and means to produce a greater change in tuning of said circuits per given increment of movement of said capacitors in the intermediate portion of the movement of said capacitors corresponding to said intermediate range of frequencies than at either end, and the constants of said circuits being so proportioned that the characteristic expressing the variation in tuning per increment of movement of the respective capacitor for said input circuit intersects said characteristic for the local oscillator in at least two places near the ends of said characteristics corresponding to points in said desired bands of frequencies.

3. The combination, in a superheterodyne receiver of a signal input circuit and a local oscillator circuit, each circuit including an inductance and a variable capacity, said variable capacities having respective movable electrodes arranged for unicontrol to tune said circuits over a low frequency range, switching means to disconnect said inductances from said capacities and to connect a respective second inductance in each circuit to adapt said circuits for tuning over a high frequency range by said variable capacities, said high frequency ranges corresponding to a range of the frequency spectrum including in its extremities respective separated bands of frequencies to be received, the variable capacity of said oscillator being smaller than the variable capacity of said input circuit and both capacities being connected across the entire coil of the respective circuit in the low frequency band and the larger of said capacities being connected through a fixed condenser across only a portion of the respective coil in the high frequency band, the constants of said circuits during reception in the high frequency band and the rate of variation of said capacities with movement of said movable electrodes being such that frequencies to which said

receiver is tuned are spaced more widely toward both ends of the range of movement of said movable electrodes than in the intermediate portion of said range.

5. The combination, in a superheterodyne receiver of a signal input circuit and a local oscillator circuit, each circuit including an inductance and a variable capacity, said variable capacities being arranged for unicontrol to tune said circuits over a low frequency range, switching means to disconnect said inductances from said capacities and to connect a respective second inductance in each circuit to adapt said circuits for tuning over a high frequency range by said variable capacities, said high frequency range corresponding to a portion of the frequency spectrum having in its ends respective bands of desired frequencies, said bands being separated in said spectrum the variable capacity of said oscillator being 10 smaller than the variable capacity of said input circuit and both capacities being connected across the entire coil of the respective circuit in the low frequency band and the larger of said capacities being connected across only a portion of the respective coil in the high frequency band, and a padder condenser connected in series with said 15 larger variable capacity of said input circuit and a trimmer capacity in shunt therewith in said high frequency band said padder and trimmer 20 being variable to track said circuits near opposite ends thereof in said bands of desired frequencies.

5. The combination, in a superheterodyne receiver having a signal input circuit and a local oscillator circuit, band switching means to connect each of said circuits for operation over different corresponding frequency bands, the higher band including two ranges of desired frequencies separated by undesired frequencies, one range falling at each end of said high frequency band, 25 a variable tuning condenser in each circuit to tune the respective circuit over the corresponding bands of frequencies, said condensers having capacitance variable by movement of a single control member, the capacitance of the condenser of 30 the signal input circuit increasing at an increasing rate with movement of said member and the capacitance of the condenser of said oscillator circuit varying at a rate greater in the intermediate portion of the range of movement of said 35 member than near the ends thereof, and reactance elements in each circuit proportioned to align the variations in tuning of said circuits with each other and to vary the tuning of said receiver in that one of said bands of higher frequency at 40 a rate reducing with movement of said member toward either end of its range of movement from a point near the middle of said range whereby 45 said ranges of desired frequencies are more widely spread out in the range of movement of said 50 control member than are said undesired frequencies.

6. The combination, in a superheterodyne receiver having a signal input circuit and a local oscillator circuit, each tunable over at least two bands of frequencies by variation of respective uncontrolled tuning condensers, the tuning condenser of the signal input circuit having capacity increasing at progressively increasing rate with variation thereof toward higher frequencies and the other condenser having capacity increasing at a rate lower near either end of its range of variation than in the middle of said range, said other capacity being connected directly across the inductance of said oscillator circuit in the higher frequency band and determining a tuning curve

between frequency and variation of said uncontrolled condensers having greatest slope at the intermediate portion thereof, and a padder in the signal input circuit for high frequencies between said tuning signal input condenser and the inductance of said high frequency input circuit proportioned to reduce the rate of variation of tuning of said input circuit toward the lower frequencies to align with the frequency variations of said local oscillator.

7. The combination, in a superheterodyne receiver having a signal input circuit and a local oscillator tunable by uncontrolled condensers over two bands of frequencies for reception by said receiver of signals in the broadcast band and in one band of higher frequencies, having frequencies to be received only near the ends thereof, a loop antenna, an inductance, means to connect said inductance in said signal input circuit for reception in the broadcast band and said loop for reception in said higher frequency band, that one of the uncontrolled condensers in said input circuit having larger capacity than the other, and said other condenser determining a tuning characteristic of said receiver in said higher frequency band having reduced slope at each end thereof, said larger capacity being connected through a padder across a portion less than all of the inductance of said loop thereby to increase the sensitivity of said receiver and being proportioned to align said input circuit with said oscillator circuit in said high frequency band whereby spreading of said frequencies to be received with respect to variation of said uncontrolled condenser occurs at both ends of said high frequency band.

8. The combination, in a superheterodyne radio receiver for reception of signals in separated bands of the short wave region, of a tuned input circuit including a variable tuning condenser, a local oscillator having a frequency determining circuit including a variable tuning condenser, said condensers being arranged for unicontrol by movement of a common element, said input circuit being tunable over a range including two of said separated bands and said local oscillator being maintained at a frequency different therefrom by a substantially fixed amount, and both of said circuits having constants such that the curve expressing the relation between frequency which said receiver is tuned to receive and the percent of the movement of said common element has maximum slope in the region between said bands and has slope sufficiently reduced in both of said bands materially to increase the facility of tuning said receiver to desired frequencies in both of said bands by movement of said common member.

9. The combination, in a superheterodyne radio receiver for reception of signals in separated bands of the short wave region, of an input circuit tunable over a range including two of said bands, one at each end thereof, said circuit including an inductance shunted by a trimming condenser, a local oscillator having a frequency determining circuit including an inductance, a pair of variable tuning condensers arranged for unicontrol by a common movable member, one of said condensers being connected across a portion of the first inductance through a series condenser to reduce the rate of change of tuning of said circuit per increment of movement of said

element in one of said bands, and said other condenser being connected directly across said other inductance and having capacity changing at reduced rate with movement of said element in said one band, and both said condensers having capacity changing at reduced rate with movement of said element to tune said receiver to frequencies in the other band, whereby the curve expressing the relation between frequency to which said receiver is tuned and position of said member has maximum slope in its middle region and reduced slope toward the extremities corresponding to said bands.

10. The combination, in a radio receiver having a pair of input circuits and an output circuit, of a band selector device having at least two positions for connecting a selected one of said input circuits to said output circuit, reactance means having a single movable element movable over a range to tune said receiver circuits over either of two bands of frequencies dependent on the position of said band selector device, one of said bands comprising the broadcast band and the other band comprising a short wave band, said one band being tuned substantially uniformly by continuous movement of said movable element between the limits of its range of movement, said short wave band including two separated bands in which desired signals are received, said last two bands being separated in said short wave band by an intermediate range, and means permanently connected in said receiver circuits cooperating with the input circuit of said short wave band and responsive to continuous movement of said movable element between the limits of its range of movement to decrease the variation of tuning of said receiver circuits over said short wave band per increment of movement of said movable element in both of said last two separated bands with respect to the variation in tuning per increment of movement of said movable element in said intermediate range.

RICHARD F. SHEA.
